UNITED STATES PATENT OFFICE

WILLIAM E. FOWLER, JR., OF HAMMOND, INDIANA, ASSIGNOR TO SIMPLEX RAILWAY APPLIANCE COMPANY, OF CHICAGO, ILLINOIS, A CORPORATION OF ILLINOIS.

BRAKE-BEAM.

No. 906,213.

Specification of Letters Patent.

Patented Dec. 8, 1908.

Application filed June 16, 1908. Serial No. 438,824.

To all whom it may concern:

Be it known that I, WILLIAM E. FOWLER, Jr., a citizen of the United States, residing at Hammond, in the county of Lake and State 5 of Indiana, have invented certain new and useful Improvements in Brake-Beams, of which the following is a specification.

My invention has relation more especially to the brake-heads of railway car brake 10 mechanisms and their means of attachment to the brake-beam proper. It is desirable to have such brake-heads readily detachable and adjustable angularly on the sleeves fitted on the beam. It is therefore the ob- 15 ject of this invention to provide a construction of this character and with the functions specified, which shall be simple in structure, comparatively cheap to manufacture, and which will securely hold the brake-head from 20 longitudinal movement on the sleeve and with the proper angular adjustment. In the preferred form of the embodiments of my invention, the brake-head is split, has a bayonet-joint connection with the sleeve, 25 and has a bolt binding together the parts of the split portion of the head, whereby it may be rotatably adjusted on the cylindrical sleeve to obtain the proper angular disposition of the brake-shoe carried by the head.

On the accompanying drawing illustrating such embodiment of my invention, Figure 1 is an end view of a brake-beam equipped with one of my improved brake-heads, the tension member being broken away; Fig. 2 is a face view of the construction shown in Fig. 1, as viewed from the left of that figure; Fig. 3 is a top plan view of an end portion of the brake-beam with the head omitted; Fig. 4 is a section of the brake-head alone on line 40 4—4 of Fig. 1, as viewed in the direction indicated by the arrows; Fig. 5 is a central horizontal section through the end of the brake-beam with the head omitted; and Fig. 6 is a cross-section of the sleeve on line 45 6—6 of Fig. 5.

The brake-beam has the usual compression and tension members 10 and 11, respectively, united at their ends by cylindrical encircling sleeves 13, each having at its inner end a 50 circular flange 14, and on its exterior cylindrical or convex surface a curved groove or slot 15 with lateral extensions 15^a and 15^b at its two ends, which extend longitudinally of and to the end of the sleeve, forming open

mouths or entrances for the curved groove 55 15. This sleeve, as is customary, is held on the ends of the compression and tension members 10 and 11 by means of a nut 16 on the threaded protruding end of the tension rod 11. The brake-head 17 has a central 60 cylindrical aperture 18 supplied with a square internal projection or boss 19 adapted to coöperate with the groove 15, 15^a, 15^b, the two forming what may be termed a bayonet joint, the projection or boss 19 being of substantially the same dimensions as the groove mentioned. At 20 the brake-head is split, this part of the head having a tightening or clamping bolt 21 passed through holes in the two portions of the head on opposite 70 sides of the device, and adapted by means of its nut to securely fasten the head on the sleeve and prevent its rotation thereon, as is readily understood.

To slip or slide the brake-head on the 75 sleeve, the former is turned so that its inner projection or lug 19 will enter one of the open ends 15^a or 15^b of the slot or groove 15 as the head is pushed on to the sleeve. After having been pushed home, the head 80 is turned angularly on the sleeve, the projection 19 then entering the curved, longer portion 15 of the groove until it is brought to the desired angular position, in which it may be clamped by tightening the nut on 85 bolt 21. The manner of adjustment or removal of the brake-head is obvious from the above description, and needs no com-ment.

It will be observed that the bayonet- 90 joint connection between the brake-head and sleeve or beam eliminates all possibility of the head becoming accidentally displaced longitudinally of the brake-beam, and that the clamping or tightening nut 95 effectually prevents unintentional turning of the head on the sleeve.

It may be noted that this invention is not restricted to the exact structural features herein shown and described, and that they 100 may be modified and changed within wide limits without departing from the substance of my invention.

I claim:

1. The combination of a brake-beam, a 105 split brake-head adapted to fit and turn on said brake-beam, a bayonet-joint connection between said brake-head and brake-beam,

2
and means to clamp said brake-head on said beam to maintain the same in adjusted angular position, substantially as described.

2. The combination of a brake-beam, a sleeve on the end of said brake-beam, a split brake-head adapted to fit and turn on said sleeve, a bayonet - joint connection between said brake-head and sleeve, and means to clamp said brake-head on said 10 sleeve to maintain the head in adjusted angular position, substantially as described.

3. The combination of a brake-beam, a cylindrical sleeve on the end of said beam, said sleeve having on its exterior surface a 15 curved groove extended transversely thereof,

and having one or more entrance grooves communicating therewith and extended to the end of the sleeve, a split brake-head with an internal projection adapted to enter and co-act with the walls of said curved groove to 20 prevent lengthwise shifting of the head on the sleeve, and means to clamp said head on said sleeve to maintain the head in adjusted angular position, substantially as described.

WILLIAM E. FOWLER, JR.
